UNITED STATES PATENT OFFICE

WILLIAM ALEXANDER, OF GLASGOW, SCOTLAND

OIL PUMP

Application filed December 28, 1931, Serial No. 583,508, and in Great Britain December 12, 1930.

The invention relates to an oil pump of the type comprising a plunger and a piston valve reciprocating, respectively, in a cylinder and a valve chamber connected with the cylinder by passages controlled respectively by the plunger and the valve.

In an oil pump according to the invention the plunger and piston valve elements are solidly connected in longitudinal direction so that they reciprocate in unison in substantially parallel paths, the cylinder and valve chamber being connected by transverse passages, of which the passage further from the point of delivery is at all times open to an annular space at the waist of the valve and is intermittently masked and unmasked by the plunger, and the other passage is intermittently masked and unmasked by the valve, said annular space at the waist of the piston valve being at no time subjected to the high pressure of delivery of the oil.

In practice the plunger and piston valve elements are given equal simultaneous movements from a common rotary element without the intervention of levers.

The piston valve is adjustable in position with relation to the plunger by rotation of a screw-threaded member coupled to the end of the piston valve and engaging a non-rotatable member connected to the plunger.

Desirably the free end of the plunger is bevelled so as to provide a transverse component of fluid pressure causing the side of the plunger to press against the end of the transverse passage controlled thereby.

The cylinder and the valve chamber are advantageously formed in a block having two segmental sides and two flat parallel sides so as to facilitate manufacture, location and assembly of the blocks, and to make for compactness where several pumps are assembled in one casing.

The block is provided with a flange permitting the block to be held in position in the casing by means of a superimposed cover suitable for one or more blocks in the one assembly, the cover being rigidly connected to the casing.

In the accompanying drawings Fig. I is a

transverse cross section of a fuel pump embodying the invention.

Fig. II is a longitudinal part section.

Fig. III is a sectional plan view.

In the drawings *q* denotes a block formed with a pump cylinder and with a valve chamber disposed in parallel, in which reciprocate, respectively, the plunger *f* and the piston valve *m*, moving jointly with the crosshead *e* slidable in the guide *k* and driven by a crank and connecting rod *d*. The plunger is prevented from rotating by the feather *z* engaging a groove in the plunger, as shown in Fig. I.

The crosshead is secured to the plunger by means of an adjustable T-headed member and screw connection *g* and is adjustably secured to the valve by means of the screw-threaded member *l* engaging a lug *h* projecting from the crosshead.

p denotes a rack meshing with the pinion *o* fixed to the spindle *n* which is restrained against endwise movement and the upper end of which engages the member *l*.

It will be seen that when the rack *p* is moved endwise, either by hand or by means of a governor or other agency, the axial position of the valve will be correspondingly adjusted in relation to the plunger, whether the pump is stationary or running.

Each block *q* has two segmental sides *j* (Fig. III) and two flat parallel sides *i*. A flange *q'* is provided at or near the upper end of the block, said flange and the segmental sides fitting corresponding recesses formed in the casing *a* to which is attached the sump *b* serving as an oil bath for the several cranks. The objects of flattening the sides of the block are to reduce the total space occupied when several blocks are assembled in one casing and to locate the blocks with their flat sides athwart the axis of the driving shaft.

The cover *r* extends over one or more blocks which are thus fixed endwise when the cover is rigidly clamped down to the casing *a*.

w and *v* denote, respectively, upper and lower transverse passages allowing fluid communication between the pump cylinder and the valve chamber. *x* denotes an annular

space at the waist of the valve and y a passage allowing fluid communication between the annular space x and the space above the valve. The cover r has a longitudinal passage s allowing fluid communication between the external source of supply of oil and the passage y .

The pump cylinder is closed at its upper end by a piece u containing a non-return valve and connected by a pipe t to the sprayer or injector of an internal combustion engine or other oil consumer.

The mode of operation is as follows:—

With the parts disposed as in Fig. I, and assuming that the plunger and valve are moving upwards, i. e., in the delivery stroke, oil is forced past the non-return valve to the point of use. Delivery continues until the upper edge of the annular space x unmasks the upper transverse passage w , whereupon in the further upward movement of the plunger the oil is returned via the passages w and y to the passage s . The point in the upward stroke of the plunger at which the oil is returned to the passage s is determined by the relative axial positions of the valve and the plunger, it being understood that the return of oil continues to the end of the delivery stroke. The lower transverse passage v is never out of communication with the annular space x , and the upper transverse passage w is never masked by the plunger.

At the top of the downward or suction stroke, the pump cylinder being in fluid communication with the passage s through the passage w , annular space x , and passage y , in the first stage of downward movement of the plunger oil is drawn through these passages into the pump cylinder. As the plunger descends, the passage w is masked by the valve, but the passage v is unmasks by the plunger and oil continues to be drawn into the pump cylinder during the remainder of the stroke.

These actions are independent of the direction of rotation of the driving shaft.

What I claim is:—

1. An oil pump comprising a cylinder adapted to deliver oil and a valve chamber substantially parallel to said cylinder, said chamber being adapted to communicate with a source of oil supply, and plunger and piston valve elements solidly connected in longitudinal direction for reciprocation in unison in said cylinder and chamber, said valve element being constricted at the waist so as to leave an annular space between said waist and the wall of said chamber, said cylinder and valve chamber being connected by transverse passages of which the passage further from the point of oil delivery from said cylinder is at all times open to said annular space and intermittently masked and unmasked by said plunger element, and the other passage is intermittently masked and unmasked by said valve element, said annular

space being at no time subjected to the high pressure of delivery of the oil.

2. An oil pump comprising a cylinder adapted to deliver oil and a valve chamber substantially parallel to said cylinder, said chamber being adapted to communicate with a source of oil supply, and plunger and piston valve elements solidly connected in longitudinal direction for reciprocation in unison in said cylinder and chamber, said valve element being constricted at the waist so as to leave an annular space between said waist and the wall of said chamber, said valve also formed with a longitudinal passage extending from its end nearer to the point of supply and open to said annular space, said cylinder and valve chamber being connected by transverse passages of which the passage further from the point of oil delivery from said cylinder is at all times open to said annular space and intermittently masked and unmasked by said plunger element, and the other passage is intermittently masked and unmasked by said valve element, said annular space being at no time subjected to the high pressure of delivery of the oil.

3. An oil pump comprising a cylinder adapted to deliver oil and a valve chamber substantially parallel to said cylinder, said chamber being adapted to communicate with a source of oil supply, plunger and piston valve elements solidly connected in longitudinal direction for reciprocation in unison in said cylinder and chamber, said valve element being constricted at the waist so as to leave an annular space between said waist and the wall of said chamber, said cylinder and valve chamber being connected by transverse passages of which the passage further from the point of oil delivery from said cylinder is at all times open to said annular space and intermittently masked and unmasked by said plunger element, and the other passage is intermittently masked and unmasked by said valve element, and a common rotary driving element directly connected to said plunger and said valve for imparting equal and simultaneous movements to said plunger and said valve.

4. An oil pump comprising a cylinder adapted to deliver oil and a valve chamber substantially parallel to said cylinder, said chamber being adapted to communicate with a source of oil supply, and plunger and piston valve elements solidly connected in longitudinal direction for reciprocation in unison in said cylinder and chamber, the free end of said plunger element being bevelled, said valve element being constricted at the waist so as to leave an annular space between said waist and the wall of said chamber, said cylinder and valve chamber being connected by transverse passages of which the passage further from the point of oil delivery

from said cylinder is at all times open to said annular space and intermittently masked and unmasked by said plunger element, and the other passage is intermittently masked and unmasked by said valve element.

5 In testimony whereof I have signed my name to this specification.

WM. ALEXANDER.
